Attest:

UNITED STATES PATENT OFFICE.

JOSEPH A. GUYER, OF MARION, INDIANA, ASSIGNOR OF ONE-HALF TO HARRY F. ANDERSON, OF MARION, INDIANA.

ELECTRIC IRON.

Application filed April 26, 1926. Serial No. 104,595.

This invention particularly relates to electric irons which may be economically manufactured in miniature form.

An important object of the present invention is to provide a novel and useful electric iron of such simplified construction that it can be manufactured cheaply and in a convenient size adapted to be used as an operable toy or as an iron for a travellers' kit.

10 Another object of this invention is to provide a novel and useful iron rest adapted to hold the base of an iron free from a supporting surface when the iron is not in use.

15 Further objects and advantages will be come apparent as the description proceeds.

While I have disclosed in the following description and in the accompanying drawings, a preferred embodiment of my improved iron, it is obvious that it is susceptible 20 of various modifications and alternative constructions, and it is not my intention to limit the invention to this exact disclosure but to cover in the appended claims all of the various modifications and constructions falling 25 within the scope of the invention.

In the drawings,

Figure 1 is an elevational view of the preferred form of the electric iron.

Fig. 2 is a sectional view of the iron taken 30 substantially along line 2-2 of Fig. 3, the raised portion of the base being shown in plan.

Fig. 3 shows a section of the iron taken along line 3-3 of Fig. 1.

35 Fig. 4 is a view similar to Fig. 3 and showing the manner in which the iron, when idle, is supported by the improved iron rest.

Fig. 5 is a plan view on a reduced scale of the iron rest.

40 In general, my invention comprises a base, a shell or cover thereon, and a heating unit located on the base within the shell. An iron rest and a handle for the iron are positioned on the shell, and a single securing means holds the various elements in operative relation.

45 In the embodiment of my invention shown in the drawings, the iron comprises a base 6 of the usual relatively triangular shape. Upstanding from the central portion of the base is a boss 7 substantially similar to the base in shape and preferably formed integrally therewith. Formed on the periphery of the base 6 is a narrow rim or flange 8

which with the boss 7 defines a shallow 55 groove or channel 9.

A hollow shell 10 is positioned upon the base in such manner that the edges of the shell rest in the shallow groove 9 against the inner surface of the rim 8. By this construction, lateral displacement of the shell 10 relative to the base 6 is prevented.

Any suitable type of heating element may be provided but that which I prefer to employ is shown herein as a single strand of 65 commercial resistance wire encased in flexible heat insulation. The heat unit or wire 11 comprises a double section of this wire positioned in the shallow groove 9 between the boss 7 and the side walls of the shell 10, the 70 loose ends of said wire being adapted to be connected to a source of current.

As a preferred means of providing an egress for the loose ends of the heating element from the interior of the iron, I have 75 shown in Fig. 1-a tubular sleeve 14 threaded into an opening in the rear top surface of the shell 10 through which opening and sleeve the wires 11 are led. The wires 11 may be secured against accidental travel 80 through the sleeve 14 by means such as a wire clamp 15.

A simplified type of handle, which utilizes the tubular sleeve 14 as a support for one end of the handle is provided. This handle 85 comprises a handpiece 16 of any suitable nonconductor of heat such as wood which is firmly fixed at one end to the tubular sleeve 14. The other end of the hand piece is secured to a strap 17 which extends downwardly and rearwardly, and which has at its lower end a portion 18 arranged to rest upon the surface of the shell.

Preferably a single means is provided to secure the strap 17 and the shell 10 to the 95 base. As shown in Fig. 3, this means comprises a bolt 19 which is threaded into the boss 7 on the base 6 and which passes through registering openings in the shell and the strap.

An iron rest 20 is also incorporated in the iron assembly by the bolt 19. The iron rest 20, Figs. 3 and 5, consists of a rigid support arranged across the top of the shell 10 between the strap 17 and the sleeve 14 and extending outwardly beyond the sides of the base 6. When the iron is overturned upon either side as in Fig. 4, the iron rest 20 with

the hand piece 16 is adapted to raise and hold the base 6 off the surface of an ironing board or table.

It is readily apparent that the iron herein disclosed is capable, because of the simplified construction and small number of parts, of being cheaply manufactured without materially decreasing the efficiency of the iron. Hence, the iron may be produced as a miniature iron for use as an operable toy, and is especially adaptable for use as an iron for travellers.

I claim as my invention:

1. An electric iron comprising, in combination, a base, a shell upon said base, a heating unit within said shell, a tubular member having screw threaded engagement with said shell near the rear end thereof to provide an egress for a part of said heating element, a handle for said iron secured at one end to the upper end of said tubular member, an angular support for the other end of said handle having one portion arranged to space

said end from the shell when the other portion extends centrally from front to rear in 25 overlying abutting relation to said shell, and a single fastening means extending through said overlying portion and said shell into engagement with said base rigidly to secure said parts in assembled relation.

2. An electric iron comprising, in combination, a base, a shell upon said base, a heating unit within said shell, an opening in said shell, a tubular sleeve threaded into said opening and providing therewith an egress 30 for a portion of said heating unit, a handle for said iron supported at one end by said sleeve, an iron rest upon said shell, said rest comprising a plate extending outwardly beyond opposite sides of said base, and a single 35 fastening means securing said iron rest, said handle and said shell to said base.

In testimony whereof, I have hereunto affixed my signature.

JOSEPH A. GUYER.
